DESIGN FOR A COOKING RANGE

Harold W. Taft, Wichita, Kans., assignor to Coleman Bottled Gas, Inc., Wichita, Kans., a corporation of Kansas

Application January 15, 1940, Serial No. 89,472

Term of patent 7 years

To all whom it may concern:

Be it known that I, Harold W. Taft, a citizen of the United States, residing at Wichita, in the county of Sedgwick and State of Kansas, have invented a new, original, and ornamental Design for Cooking Ranges, of which the following is a specification, reference being had to the accompanying drawing, forming part thereof.

Fig. 1 is a perspective view of a cooking range, showing my new design.

Fig. 2 is an elevational view of one side of the

range, the other side being substantially the same as that shown.

The design is characterized by the offset cooking top extending in continuous formation across the working top and the splash panel in combination with the range shown.

I claim:

The ornamental design for a cooking range, as shown and described.

HAROLD W. TAFT.
